COMBINED PENHOLDER, STORAGE BOX, MEMO PAD, AND CALENDAR HOLDER

George A. Aro, 2925 18 Ave. N., Minneapolis, Minn.

Filed Mar. 16, 1964, Ser. No. 79,014

Term of patent 14 years

(Cl. D74—5)

FIG. 1 is a side, perspective view of a combined penholder, storage box, memo pad, and calendar holder, showing my new design.

The side and back are plain and unornamented.

FIG. 2 is a reduced side perspective view thereof as it appears in use, the broken line showing of a telephone in this view being for illustrative purposes only;

FIG. 3 is a front elevational view with parts thereof being shown broken away for convenience of illustration; and

FIG. 4 is a side elevational view of the design shown in FIG. 1.

I claim:

The ornamental design for a combined penholder, storage box, memo pad, and calendar holder, substantially as shown and described.
